UNITED STATES PATENT OFFICE.

WALTER P. COLEMAN, OF ATLANTA, GEORGIA.

SAFETY-RAZOR GUARD.

1,405,759.

Patented Feb. 7, 1922.

Application filed October 21, 1920. Serial No. 418,388.

To all whom it may concern:

Be it known that I, WALTER P. COLEMAN, a citizen of the United States, residing at Atlanta, in the county of Fulton and State 5 of Georgia, have invented certain new and useful Improvements in Safety - Razor Guards, of which the following is a specification.

In the process of shaving it is customary 10 to manipulate the razor with one hand while the other hand is utilized to stretch the skin upon the surface immediately to be shaved for the purpose of preventing the surplus flesh from bunching or rolling up in advance of the razor blade under pressure produced by the razor, most frequently resulting in cutting unless great care is exercised. This rolling up of the loose flesh takes place regardless of the type of razor employed, 20 but is especially attended with disastrous results in the use of what is known as the straight or old fashioned razor.

Resort has been had in the past to the use of the so-called safety razor to eliminate 25 at least partially the tendency for one to cut himself, but even with this type the same objection above referred to prevails, that is, the flesh rolls up under pressure of the guard, usually forming a part of the 30 safety razor construction, in fact, it is noticeably greater than where the old type of razor having no guard is used. However, the advantages of the safety razor predominate this disadvantage and we now have 35 special guards which are applicable to the old or straight type of razor, so-called, so as to convert them into the safety type.

With this in view the object of the present invention is to provide a device which is 40 associated with the razor blade, preferably in the form of an attachment, and which acts upon the flesh to stretch the same just in advance of the blade edge quite similar to the stretching produced by the hand so as to 45 present to the edge of the blade a substantially flat surface over which to cut. The invention might readily be devised for this purpose only, but I prefer in carrying out my object to incorporate the novel feature 50 which accomplishes the stretching action referred to as a part of the safety blade guard, and to this end said guard is formed with what I term an extension operating in advance of the blade edge protector, the former 55 to roll up the surplus flesh and stretch it

from the point where the latter is firmly pressed and resists its movement.

Other objects and advantages will become apparent from the following description and the accompanying drawings in which:—

60

Figure 1 is a perspective view of a razor construction showing the invention applied in operative position thereupon;

Figure 2 is a front elevation of the guard forming the special subject matter of this 65 invention;

Figure 3 is a sectional view on the plane indicated by the line 3—3 of Fig. 1;

Figure 4 is a fragmentary sectional view 70 considerably enlarged to show more clearly the details of construction and cooperative relation of the guard parts and blade; and

Figure 5 is a view similar to Fig. 4 but showing the edge 4 of the guard slightly offset from the plane of the edge 3 as herein-after set forth.

Throughout the following detail description and on the several figures of the drawings, similar parts are referred to by like 75 reference characters.

80

Referring to the drawings, A designates a blade holder, the specific construction of which forms the special subject matter of a co-pending application, and for this reason need not be more specifically described herein, B the handle for said holder and C the removable razor blade.

85

Referring to Fig. 2 particularly, the invention consists of a guard constructed from sheet metal or other suitable material, the body 1 of which is of a length corresponding to the length of the razor blade edge. At one side the body is formed with a plurality of gripping flanges 2 bent into spaced relation to the body 1 and adapted to engage 90 about the blade holder for purposes of attaching the apparatus to the same after the manner illustrated in Fig. 1 of the drawing. The flanges referred to possess sufficient resiliency to frictionally hold the guard against accidental displacement in cooperative relation to the blade. At a point approximate the edge of the blade the guard is bent or otherwise formed with a longitudinally extending protector edge 3, which term 100 I use merely for the purposes of distinguishing the same from a quite similar edge 4 of the guard extension and which latter edge I will term for the same reason the tensioning edge. The edge 4 may be in alignment 110

with 3 as shown in Fig. 4, or as shown in Fig. 5, the edge 4 may be slightly offset from the plane of the edge 3, which latter edge in the operation of shaving is substantially equivalent to the guard edge of the ordinary safety razor guard used with this type of razor. The edge 3, in other words, has a limiting tendency in the usual construction as far as pressure against the flesh is concerned, whereby to prevent cutting of the flesh accidentally. But in these usual constructions as above premised, it is still a necessary matter to stretch the skin away from this pressure edge or the cutting is likely to take place. On the contrary, with my device the edge 4 takes care of this surplus flesh by rolling it in advance of and away from the blade edge, which action is somewhat resisted by the light pressure of the edge 3 upon the flesh. The result of a movement of the article over the flesh is that the latter is stretched between the two edges 3 and 4 so that the razor blade will actually operate upon a substantially flat or smooth surface. I particularly construct the edges 3 and 4 of this guard to insure smoothness so that the device will move with facility over the flesh without too great frictional resistance. The body of the guard at the point 5 is bent inwardly slightly so as to properly position the edge of the blade in slightly spaced relation to the edge 3, and the metal between this point and said edge as well as between the edges 3 and 4 both spaces of which are bowed outwardly, is cut out with a series of openings or apertures 6'. Obviously the pressure of the operator upon the edge 4 of the guard may be increased to such an extent as to increase the space between the cutting edge of the blade and the pressure edge 3 of said guard to thereby control the cutting action of the blade so as to permit of obtaining a close shave or one not so close.

With this construction it will be apparent that the invention renders the safety razor doubly safe against accidental cutting of the flesh and relieves the operator of the necessity of stretching the skin with his free hand. It will furthermore be understood that the protector guard may be readily removed from the razor and applied in reverse position so as to enable shaving of both sides of the face, and for cleansing purposes as customary. The additional features of construction are of a simple character and do not materially increase the cost of manufacture of the guard.

What I claim as new and desire to secure by Letters Patent of the United States is:—

1. The combination with a razor blade, of a guard device therefor arranged at one

side of said blade and formed with a face-engaging edge intermediate its length extending parallel with and in close proximity to the razor blade cutting edge, and a second face-engaging edge slightly spaced from the first mentioned edge and disposed in advance of the razor blade edge, said two edges being co-extensive in length with the razor blade edge.

2. A new article of manufacture comprising a slip on guard attachment for razor blades having at one side gripping means for holding the attachment upon a razor in juxtaposed relation to its blade and at its other side spaced edges free from the first-mentioned side and engageable with the flesh, one substantially in advance of the blade edge and the other approximate the blade edge.

3. A new article of manufacture comprising a guard attachment for razor blades having at one side gripping means for holding the attachment upon a razor in juxtaposed relation to its blade and at its other side spaced edges engageable with the flesh, one substantially in advance of the blade edge and the other approximate the blade edge, the material between the said spaced edges being bowed outwardly from the plane of said edges.

4. A new article of manufacture comprising a safety guard for razor blades having gripping flanges at one side thereof and at its other side a pair of spaced longitudinally extending edges free from the first-mentioned side and adapted to contact with the surface of the flesh in advance of the blade edge, one of said edges being offset with respect to the plane of the body of the guard.

5. A new article of manufacture comprising a safety guard for razor blades including a body having means for securing the same to a razor, and flesh stretching edges arranged in spaced relation approximate the edge of the blade, said body being of resilient material whereby pressure upon one of said edges will regulate the position of said edges with respect to and control the cutting action of the blade.

6. A safty razor guard of the class described comprising a body having means bent therefrom to provide gripping action to hold the guard in cooperative relation with respect to the blade and a flesh contacting edge arranged in advance of the edge of the razor blade upon which pressure may be exerted to regulate the cutting action of said razor blade.

In testimony whereof I affix my signature.

WALTER P. COLEMAN.
